Nº 3555

— Alexander Wemyss —
— Design for the Body of a Frame for Mica —
— Stove Doors —

PATENTED
JUN 22 1869

John Parker

Alex. Wemyss

United States Patent Office.

ALEXANDER WEMYSS, OF PHILADELPHIA, PENNSYLVANIA, ASSIGNOR TO STUART, PETERSON, AND COMPANY, OF SAME PLACE.

Design No. 3,555, dated June 22, 1869.

DESIGN FOR THE FRAME OF A STOVE-DOOR.

The Schedule referred to in these Letters Patent and making part of the same.

To all whom it may concern:

Be it known that I, ALEXANDER WEMYSS, of Philadelphia, county of Philadelphia, State of Pennsylvania, have originated a new Design for the Body of a Frame for Mica Stove-Doors; and I do hereby declare that the accompanying drawing and following explanation thereof, form a full, clear, and exact description of the said design.

In the drawing, the figure represents a front view of my design for the body of a frame for mica doors for stoves, the said frame consisting of two oval figures united in the manner clearly indicated in the drawing, each oval space being furnished with a plate of mica, and presenting a neat and ornamental appearance.

The frame is susceptible of being ornamented with a variety of minor designs, outlines of one class of ornaments being shown in red lines.

I claim the design for the body of a frame for stove-doors, substantially as described, and as illustrated in and by the accompanying drawing.

In testimony whereof, I have signed my name to this specification, in the presence of two subscribing witnesses.

ALEX. WEMYSS.

Witnesses:

H. HOWSON,
JOHN WHITE.
